UNITED STATES PATENT OFFICE.

DAVID P. SIMS, OF LINCOLN, NEBRASKA, ASSIGNOR TO THE SIMS HYDRAULIC ENGINE COMPANY, OF SAME PLACE.

IMPACT WATER-MOTOR.

SPECIFICATION forming part of Letters Patent No. 644,833, dated March 6, 1900.

Application filed November 18, 1898. Serial No. 696,830. (No model.)

To all whom it may concern:

Be it known that I, DAVID P. SIMS, a citizen of the United States of America, residing at Lincoln, in the county of Lancaster and State of Nebraska, have invented certain new and useful Improvements in Impact Water-Motors; and I do hereby declare the following to be a full, clear, and exact description of my invention, such as will enable skilful mechanics to construct the same, by reference to the accompanying drawings, and to letters of reference marked thereon, which form part of this specification.

The object of this invention is to provide a motor of which the power to operate shall be water under pressure, the power of which may be transmitted to a water-wheel, which it causes to revolve either to the right or left, as the operator may wish.

These motors will be of special value to dentists to drive their dental engines and lathes, being entirely under their control by means of a foot-switch, by which the motor is started, stopped, reversed, and the rate of speed controlled.

In the accompanying drawings, forming part of this specification, Figure 1 is a vertical section through the valve-chamber. Fig. 2 is a sectional view through one of the buckets on the rotary water-wheel. Fig. 3 is a top plan view of a bucket. Fig. 4 is a sectional view through a portion of a bucket. Fig. 5 is a detail view of a clamping member. Fig. 6 is a vertical section through the valve-chamber and water-wheel. Fig. 7 is a sectional view through the water-wheel chamber and nozzles leading thereto, the water-wheel being shown in elevation. Fig. 8 is a detail view of an apertured disk. Fig. 9 is a detail view of a treadle mechanism. Fig. 10 is a cross-sectional view through the treadle. Fig. 11 is a sectional view through the treadle and pulley, and Fig. 12 is a top plan view of the treadle.

Reference now being had to the details of the drawings by letter, *v* designates the base of the water-chamber, having a water-inlet *d* and outlets *o* and *g*. Over the outlet passage-ways are the valves *c*, made of leather or other suitable material and having corresponding ends fixed to the inner circumference of the

water-chamber by means of the clamp-brackets *a*, held to the chamber by screws *m*. Mounted in the side walls of the water-chamber is the shaft *n*, on which are lateral arms *T*, and connecting each end of an arm to a free end of a valve *c* is a chain *r*. Over the outlet passage-ways *g* and *o* are the disks *i*, having series of different-sized apertures *i* therein, so as to allow the supply of water to gradually enter the passage-ways leading to the water-wheel. Connecting the passage-ways with the pipes *l* are unions *k*, said pipes having nozzles *u*, as shown, which enter apertures on opposite sides of the casing *y*, which contains the water-wheel. Upwardly and outwardly inclined ears *u'* on the casing adjacent to said apertures are provided, the upper surfaces of which ears are continuous with the lower margins of the inclined apertures *u* in which the nozzles engage and serve to retain the latter in the positions shown in Fig. 7 of the drawings. Mounted in the side walls of said chamber is a shaft *p*, on which is keyed a water-wheel *h*, having a series of buckets or pockets *e* about its circumference, which buckets are S-shaped in end or top elevation, as shown in Fig. 3. These S-shaped or double buckets have their upper free edges slightly curved, as shown in Figs. 8 and 4, to receive the full force of the water when turned on from either nozzle.

Mounted on the shaft *n* is a pulley *j*, grooved and held to said shaft by means of a key *R*. Access is had to the interior of the water-chamber by means of removing the threaded disk or plate *N*. The shaft *n* may be oiled through duct *M*.

For operating the pulley which actuates the valves in the water-chamber I provide a treadle *w*, having ears *w'*, pivoted to the uprights *v'* on the plate *v*. At one end of said treadle is a lug *w*, having an elongated slot *w*, in which slot a lug *X*, carried by the pulley *X'*, engages. This pulley *X'*, which has a grooved circumference, is mounted on a stub-shaft *X*, mounted in the upright portion of the plate *v*. An endless cable *Y* passes about the pulleys *X'* and *j*, and by tilting said treadle the pulley *j* will be rocked backward and forward and the valves *c* alternately opened and closed when it is de-

sired to have the water-wheel rotated in one direction or the other.

What I claim is—

1. In combination with the casing, the water-wheel mounted therein, the ears u' , the nozzles held in inclined apertures in the casing by said ears, and the S-shaped buckets, with their upper edges curved, disposed about the circumference of said wheel, whereby the full force of water from either nozzle is brought to bear against the buckets, as set forth.
2. In combination with the valved chamber, the shaft mounted therein and the pulley

mounted thereon, the treadle having a lug w^2 with elongated slot w^3 therein, the pulley X' and plate supporting same, the lug X carried by the pulley X' and engaging in said slot, and the cable passing about said pulleys, as shown and described.

In testimony whereof I affix my signature 20 in presence of two witnesses.

DAVID P. SIMS.
